UNITED STATES PATENT OFFICE.

ERASTUS E. WINKLEY, OF LYNN, MASSACHUSETTS, ASSIGNOR, BY MESNE ASSIGNMENTS, TO UNITED SHOE MACHINERY CORPORATION, OF PATERSON, NEW JERSEY, A CORPORATION OF NEW JERSEY.

BOOT AND SHOE.

Application filed May 18, 1917, Serial No. 169,382. Renewed March 22, 1920. Serial No. 367,890.

To all whom it may concern:

Be it known that I, ERASTUS E. WINKLEY, a citizen of the United States, residing at Lynn, in the county of Essex and 5 State of Massachusetts, have invented certain new and useful Improvements in Boots and Shoes; and I do hereby declare the following to be a full, clear, and exact description of the invention, such as will enable 10 others skilled in the art to which it appertains to make and use the same.

The present invention relates to an improvement in boots and shoes, and more especially to an improvement in the bottoms 15 of boots and shoes, particularly the heel.

In that process of constructing boots and shoes in which the outsole is of less length than the boot or shoe as a whole, a short projection or tongue extending rearwardly 20 from the shank portion of the outsole is received in a correspondingly shaped recess at the breast of the heel seat of the heel, so that the face of the heel seat and the flesh side of the outsole of the shoe-bottom 25 thus constructed form one continuous surface. When such a heel and short outsole are applied to the lasted shoe, the margin of the heel seat of the heel presses immediately against the counter portion of the 30 upper, which has been lasted over the heel seat of the insole. This leaves an air space inside of the infolded edge of the upper between the heel and the insole. If this space is not filled, when the heel is attached 35 to the shoe the insole will be drawn by the heel nails into contact with the heel, forming a depression or cup inside the shoe which is both unsightly and uncomfortable to the wearer of the shoe. Furthermore, 40 the strain on the insole is liable to cause the upper above the rand to draw away from the heel, which produces a "grinning" joint at this part of the shoe, an undesirable feature as those skilled in the art will recognize.

It is therefore desirable to fill in this air space, and for this purpose a filler composed of leather or leatherboard and cut to the requisite shape and thickness has heretofore been used. The expense incident to 45 the production of this separate filler, as well as the time required to put it in place in the shoe, is objectionable. It is accordingly proposed to eliminate this expense by producing a heel, suitable for incorporation in

a shoe with a short outsole, of such construction that the necessity of employing a separate filler for the space referred to between the heel and the insole is eliminated. To this end the invention comprises the novel heel, and the improved shoe-bottom including said heel, hereinafter described and particularly pointed out in the appended claims.

The preferred form in which it is contemplated embodying the invention is illustrated in the accompanying drawings, in which Figure 1 is a plan view looking at the flesh side of the sole, of an assembled heel and sole of the character hereinbefore referred to, before attachment to a shoe; Fig. 2 is a transverse section through the counter portion of a shoe with the heel of Fig. 1 attached; and Fig. 3 is a perspective view of the novel heel before attachment to a shoe.

The present improved heel is applicable to any type of boot or shoe having an outsole which is of less length than the boot or shoe as a whole. In the illustrated embodiment of the invention the outsole 6 may be of any suitable pattern and is provided at the rear end of the shank with a rearwardly extending projection, or tongue, 8 which is adapted to be received in a correspondingly formed recess 10 at the breast of the heel seat of the heel 12, both of which parts are formed preferably, although not necessarily, as illustrated in my Letters Patent of the United States No. 1,396,801, granted November 15, 1921. It is to be understood that the material of which the heel is composed and the manner of constructing it, with the exception of the configuration of the heel seat 14, are no part of the present invention.

During the construction of the shoe, the lasting of the upper 16 to the insole 18 leaves a depression within the infolded edge 20 of the upper, which, in order to secure a firm heel seat and prevent checking at the joint between the heel and upper, is usually taken up by a filler.

The necessity of providing a separate filler for the space just referred to is obviated in the present invention by providing a filler piece forming a part of the heel seat of the heel. This filler piece is formed, preferably as a projection 22 rising from

the central part of the heel seat, the front wall 24 of which is a continuation of the rear wall of the breast recess 10. The surface of the projection 22 lies in a plane above the 5 flesh side of the sole as shown by the shade line in Fig. 1, and also in Fig. 3 where the relation of the thickness of the sole to the wall 24 is indicated by the dotted line 26. The raised filler piece 22 may conveniently 10 be produced by forming a recess 28 which extends along the margin of the heel seat from breast corner to breast corner, and forms a continuation of the surface of the flesh side of the outsole which fits into the recess 10. 15 This marginal recess 28 may be skived in the heel seat or it may be formed by compression, the method of forming the recess 28 in order to secure the requisite shape and height of the filler piece 22 being immaterial. 20 The marginal recess 28 is adapted to receive the infolded edges 20 of the counter portion of the upper, when the heel is incorporated in a shoe, so that the upper face of the filler piece 22, produced by the recess, 25 is permitted to bear directly against the insole, as shown in Fig. 2, and thus form a smooth, solid tread for the heel of the wearer of the shoe.

While the features of the invention have 30 been shown and described in their preferred embodiment, it will be understood that the invention may be embodied otherwise than as shown in the drawings and described in the specification and yet be within the scope 35 of the following claims.

Having thus described the invention, what is claimed as new is:—

1. A heel for boots and shoes having its heel seat face provided with a marginal recess 40 to receive the infolded edges of the counter portion of the upper, leaving the central part of its heel seat in a higher plane than the recessed marginal portion, and having a breast-end recess to receive the shank-end of a short outsole.

2. A heel for boots and shoes having its heel-seat face provided with a marginal recess of only sufficient depth to receive the infolded edges of the counter portion of the 50 upper, and also provided with a breast-end recess of greater depth to receive the shank-end of a short outsole.

3. A heel for boots and shoes having a recess at the breast portion of its heel seat 55 to receive a correspondingly shaped tongue of the outsole, and a projection adjoining said recess rising from the central part of said heel seat.

4. A shoe-bottom having, in combination, a sole provided, at the rear end of its shank portion, with a short rearwardly projecting tongue; and a heel having its heel seat provided with a breast recess to receive said tongue and with a marginal recess, adapted to receive the infolded edges of a counter portion of the upper when the shoe-bottom is applied to a lasted shoe.

5. A shoe-bottom having, in combination, a sole provided, at the rear end of its shank portion, with a short rearwardly projecting tongue; and a heel having its heel seat provided with a breast recess to receive said tongue and with a central projection against which the rear end of said tongue abuts, and of a height above the bottom of the recess 75 greater than the thickness of the sole.

6. A shoe-bottom having, in combination, a short outsole, an insole to which the infolded edges of the counter portion of the upper are attached, and a heel engaging said infolded edges and having a raised central portion against which the insole rests for filling in the space between said infolded edges.

7. A shoe-bottom having, in combination, 85 an insole to which the infolded edges of the counter portion of the upper are attached; a heel having its heel-seat face provided with a marginal recess to receive said infolded edges, leaving the central part of 90 the heel seat in a higher plane than the recessed portion to support the insole, and a short outsole abutting against the forward edge of said raised central part.

8. A shoe-bottom having, in combination, 95 a sole provided at the rear end of its shank portion with a rearwardly projecting tongue; a heel provided at the breast-end of its heel-seat face with a tongue-receiving recess and with a marginal recess extending along the 100 sides and back of the heel; and an insole to which the infolded edges of the counter portion of the upper are attached, said insole resting directly upon the central unrecessed part of the heel and the infolded edges 105 lying in said marginal recess.

9. A heel for boots and shoes having a marginal recess extending along the sides and back of the heel to receive the infolded edges of the counter portion of the upper, 110 and a central raised portion adapted to support the insole, said central raised portion being indented from the breast of the heel to provide a support for the shank-end of a short outsole.

ERASTUS E. WINKLEY.
